US00D827336S

(12) United States Design Patent (10) Patent No.: US D827,336 S
Larsen et al. (45) Date of Patent: * Sep. 4, 2018

(54) SEAT COVER

(71) Applicants: Ryan H. Larsen, Smithfield, UT (US);
Adam W. Corbett, Logan, UT (US)

(72) Inventors: Ryan H. Larsen, Smithfield, UT (US);
Adam W. Corbett, Logan, UT (US)

() Term: 15 Years

(21) Appl. No.: 29/599,802

(22) Filed: Apr. 6, 2017

(51) LOC (11) Cl. 06-13

(52) U.S. Cl.

USPC D6/611

(58) Field of Classification Search

USPC D6/610, 611

CPC B60N 2/60; B60N 2/58; B60N 2/5825

(57) CLAIM

The ornamental design for a seat cover, as shown and described.

DESCRIPTION

FIG. 1 is a front perspective view of a seat cover;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate features that form no part of the claimed design.

1 Claim, 5 Drawing Sheets
